UNITED STATES PATENT OFFICE

LEROY C. DOANE, OF MERIDEN, CONNECTICUT, ASSIGNOR TO THE MILLER COMPANY, OF MERIDEN, CONNECTICUT, A CORPORATION OF CONNECTICUT

LIGHTING UNIT

Application filed March 9, 1927. Serial No. 173,832.

The present invention relates to lighting units and is more particularly directed toward a totally inclosed lighting unit having a metallic deflector for directing the light onto the ceiling, and a diffusing plate so arranged underneath the deflector that light is transmitted downwardly and redirected so as to illuminate the outside of the deflector.

The principal object of the present invention is to provide a totally inclosed lighting unit of the above type so as to prevent the accumulation of dust and foreign matter in the deflector and on the diffusing plate.

The present invention contemplates a lighting unit of this type wherein the parts are so arranged that they may be readily assembled and disassembled and wherein a glass cover arranged above the deflector may be temporarily supported in an elevated position to permit raising the deflector and subsequent removal of the lower glass plate and deflector if desired.

Another object of the invention is to provide a lighting unit with a shade or similar part which may be lifted relative to the lamp socket and held in elevated position in a simple manner.

Certain features of construction herein shown and described form the subject matter of a copending application 173,831, filed March 9, 1927.

The accompanying drawings show for purposes of illustrating the invention, one of the many possible embodiments in which the invention may take form, it being understood that the drawings are illustrative of the invention rather than limiting the same.

In these drawings:

Figure 1 is a sectional view with parts in elevation showing a lighting unit of the above type, parts being shown in an elevated position in dotted lines;

Figure 2 is a detached elevational view of a socket housing and locking ring;

Figure 3 is a top plan view of the construction shown in Figure 2; and

Figures 4 and 5 are elevational views illustrating the assembly of the lighting unit.

A lamp socket 10 is supported in any convenient manner inside a drawn sheet metal

socket housing 11, and this socket housing is carried in the lower end of a loop 12 preferably externally threaded as indicated at 13. A lamp 14 is carried in the lamp socket in the usual manner. As here shown, the lower end 55 of the socket housing 11 supports three straps 15, 16 and 17. The upper ends of these straps are bent inwardly as indicated at 18 to pass through holes in the socket housing 11. These holes are at the upper ends of depressions 60 made in the side of the wall of the socket housing to accommodate the thickness of the straps.

A locking sleeve 19 is slidably carried on the outside of the socket housing 11 and is 65 held in place by a rivet 20 fastened to the socket housing 11 passing through a Z-shaped slot 21 in the sleeve. This slot is so shaped that it will lock the sleeve in either the lower or the upper position or permits sliding it 70 from one position to the other. When the sleeve is raised, the holes in the socket housing are available for inserting the ends 18 of the straps, and, when the ring 19 is moved down to the full line position indicated in 75 Figures 1 and 2, the upper ends of these straps are locked in position.

The upper portions 22 of the straps are comparatively close to one another, being sufficiently spaced to accommodate the neck of the 80 lamp bulb, while the lower portions 23 of the straps are spread apart as indicated, and a ring 24, here shown as a sheet metal stamping. According to the construction herein illustrated, the lower ends of the straps are 85 provided with outwardly projecting feet 25 which pass through holes 26 in the ring 24 so as to support the ring. In assembling this form of strap and ring, the lower ends of the straps are passed through the holes 26 in the 90 stamping 24 and the upper ends of the straps are then brought close together and attached to the socket cover as above described.

The construction so far described provides a substantially rigid frame work for supporting the right controlling parts of the 95 lighting unit which will now be described.

An outer cover member 27, which may take the form of a cup-shaped sheet metal stamping, is arranged so as to pass downwardly 100

about the socket housing 11 and the ring 19. It is designed to cover the housing and ring, and the neck of the bulb 14. The lower end or skirt 28 of the outer cover member 27 carries a number of straps 29 held in place by thumb screws 30. These straps 29 are bent as indicated so as to engage underneath a shade, here shown in the form of a comparatively flat glass cover plate 31. The 10 cover member 27 may be clamped in the lower position by a ring 32 threaded onto the loop 12. In order to permit raising the glass cover plate 31 and stamping 27 and support them in the raised position, the ring 19 is outwardly flanged at its upper end as indicated at 33, and this flange is cut away as indicated at 34 in line with the hook shaped members 29. The severed portions of the flange 33 are bent upwardly as indicated at 35. This construction permits raising the cover to pass the hooks 29 through the openings in the flange 33. The parts may then be relatively turned and the hook members 29 will then rest in the flange 33 between the upwardly bent prongs 20. 35. The flange 33 preferably fits the inner wall of the cover 27 so that the cover is held in alignment.

A deflector 36, preferably made of sheet metal and curved as indicated, is arranged 30 about the light source 14. The lower small diameter part 37 of the deflector is slightly larger in diameter than the ring 24, while the upper part 38 of the deflector is approximately the same diameter as the glass cover 35 plate 31. A glass diffuser 40 is arranged underneath the light source. As here shown, this glass diffuser is somewhat larger in its external diameter than the ring 24. The upper part of the glass diffuser extends inwardly in the form of a flange or lip as indicated at 41 so as to overlie the outwardly extending feet 25 of the supporting straps 15, 16 and 17.

In assembling the lighting unit, the upper 45 glass cover plate 31 is fastened to the cover member 27 and passed far enough up along the chain to permit attaching the straps 15, 16 and 17 to the socket housing. The cover plate 31 and stamping 27 may be supported on the flange 33 as above described. The deflector 36 may be passed into position by turning it at an angle as indicated in Figure 4 and passing it up above the ring 24 to bring it to the position indicated in Figure 5. Then 50 the glass diffuser 40 may be passed about the ring 24 as indicated in Figure 5 and turned about so that the inwardly directed flange 41 will rest on the feet 26. The glass cover may then be lowered to the full line position indicated in Figure 1.

When one desires to clean the inside of the unit or to renew the lamps, the cover plate may be raised to the dotted line position of Figure 1 and supported as above described, 55 then the deflector is lifted sufficiently to per-

mit removing the diffuser. The deflector may then be lowered onto the feet 25 and the unit may be cleaned or the lamp renewed without collapsing the supporting frame.

The cover plate 31 is preferably transparent and it therefore permits light to pass upwardly without interference. It of course may be made diffusing if desired. The lower glass plate 40 is preferably of diffusing glass and diffuses the light downwardly underneath the lamp. Some of the light, however, is reflected by the upper surface of the diffuser and allowed to pass upwardly through the inwardly directed lip or flange 41 of the diffuser so as to fall onto the outside surface of the deflector 36, thereby illuminating it. The path of such a ray is indicated by the letter "X".

From the foregoing it will be apparent that there has been provided a totally enclosed dust proof lighting unit of the semi-indirect type which may be shipped in a knocked down condition and assembled by anyone.

It is obvious that the invention may be embodied in many forms and constructions within the scope of the claims, and I wish it to be understood that the particular form shown is but one of the many possible forms. Various modifications and changes being possible, I do not otherwise limit myself in any way with respect thereto.

What is claimed is:

1. In a lighting unit, a lamp socket, a lamp in the socket, a socket housing, a support for the socket housing, a cover normally supported from the top of the socket housing and surrounding the socket housing and neck of the lamp, a shade, and means for supporting the shade and cover in an elevated position, said means including parts which permit raising the cover when in one angular position and prevent lowering it when in the other angular position.

2. In a lighting unit, a lamp socket, a lamp in the socket, a socket housing, a support for the socket housing, a cover normally supported from the top of the socket housing and surrounding the socket housing and neck of the lamp, a shade, a plurality of shade supporting members carried by the lower end of the cover, and a member carried by the socket housing having cut away portions to permit the shade supporting members to pass by when the cover and shade are raised, and other portions to support the shade supporting members when the cover is turned angularly.

3. In a lighting unit, a lamp socket, a lamp in the socket, a socket housing, a support for the socket housing, a cover normally supported from the top of the socket housing and surrounding the socket housing and neck of the lamp, a shade, a plurality of shade supporting members carried by the lower

- end of the cover, and an outwardly flanged ring carried by the socket housing and engaging the inner wall of the cover, the ring having cut away portions to permit the shade supporting members to pass by when the cover and shade are raised, and other portions to support the shade supporting members when the cover is turned angularly.
4. In an enclosed lighting unit, in combination, a light source, an upwardly diverging deflector for redirecting light upwardly, a support for the deflector, a light transmitting cover plate, supports for the cover plate to hold it closely adjacent the deflector or elevated a substantial distance above it, and a glass diffuser carried underneath the deflector, the diffuser having an inwardly directed flange adjacent the deflector to prevent the entrance of dust.
5. An inclosed lighting fixture comprising a central, downwardly opening lamp socket, a lamp in the socket, a socket housing, a horizontal ring below the lamp, side rods for supporting the ring from the socket housing, an outwardly and upwardly flaring deflector carried by the ring for deflecting light upwardly, a cover outside the socket housing, and a transparent glass cover plate carried by the cover and extending over to the upper edge of the deflector.
6. An inclosed lighting fixture comprising a central, downwardly opening lamp socket, a lamp in the socket, a socket housing, a horizontal ring below the lamp, side rods for supporting the ring from the socket housing, an outwardly and upwardly flaring deflector carried by the ring for deflecting light upwardly, a cover outside the socket housing, a transparent glass cover plate carried by the cover and extending over to the upper edge of the deflector, and devices for supporting the cover and cover plate spaced above the deflector.
7. An inclosed lighting fixture comprising a central, downwardly opening lamp socket, supporting devices for the lamp socket, a lamp in the socket, an outwardly and upwardly flaring deflector surrounding the lamp and arranged to upwardly reflect horizontally emitted light, means for removably supporting the deflector, said means including members extending inwardly and upwardly from the lower edge of the deflector and passing adjacent the neck of the lamp, the parts being so interrelated that it is necessary to first raise the deflector before it can be removed, a light transmitting glass cover plate for the deflector, and means for supporting the cover plate in two positions in one of which the outer edge is adjacent the upper edge of the deflector and in the other of which the plate is raised to permit raising the deflector for removal.
8. An inclosed lighting fixture comprising a central, downwardly opening lamp socket, supporting devices for a lamp socket, a lamp in the socket, an outwardly and upwardly flaring deflector surrounding the lamp and arranged to upwardly reflect horizontally emitted light, a glass diffuser underneath the lamp, the diffuser having an internal lip on which the lower edge of the deflector rests, means for removably supporting the deflector and diffuser, said means including members extending inwardly and upwardly from the lip of the diffuser and passing adjacent the neck of the lamp, the parts being so interrelated that it is necessary to first raise the deflector before the diffuser or deflector can be removed, a lighting transmitting glass cover plate for the deflector, and means for supporting the cover plate in two positions in one of which the outer edge is adjacent the upper edge of the deflector and in the other of which the plate is raised to permit raising the deflector for removal.
9. An inclosed lighting fixture comprising a central downwardly opening lamp socket, supporting devices for the lamp socket, a lamp in the socket, an outwardly and upwardly flaring deflector surrounding the lamp and arranged to upwardly reflect horizontally emitted light, a socket housing, means for removably supporting the deflector, said means including members extending inwardly and upwardly from the lower edge of the deflector and passing adjacent the neck of the lamp, and attached to the socket housing, the parts being so interrelated that it is necessary to first raise the deflector before it can be removed, a cover for the socket housing, a lighting transmitting glass cover plate for the deflector attached to the housing cover, and means for supporting the cover plate and housing cover in two positions in one of which the outer edge of the cover plate is adjacent the upper edge of the deflector and in the other of which the cover plate is raised to permit raising the deflector for removal.
